UNITED STATES PATENT OFFICE.

RALPH H. CHANDLER, OF NORWALK, OHIO.

NECKTIE-STRETCHER.

1,179,280.

Specification of Letters Patent.

Patented Apr. 11, 1916.

Application filed March 6, 1915. Serial No. 12,616.

To all whom it may concern:

Be it known that I, RALPH H. CHANDLER, a citizen of the United States, residing at Norwalk, in the county of Huron and State 5 of Ohio, have invented certain new and useful Improvements in Necktie-Stretchers; and I do hereby declare the following to be a full, clear, and exact description of the invention, such as will enable others skilled 10 in the art to which it appertains to make and use the same.

This invention relates to necktie stretchers, and one of the principal objects of the invention is to provide a stretcher and hanger 15 for four-in-hand scarfs and neckties which shall be simple in construction, inexpensive to manufacture and which will operate efficiently for holding a tie in smooth and extended position until it is ready for use.

Another object of the invention is to provide a necktie stretcher and hanger which may be made of a single piece of spring wire 20 bent into proper shape and adapted to be inserted within the large end of the tie for stretching the same and a device of similar construction adapted to be inserted in the small end of the tie, thus providing means for stretching the tie both transversely and longitudinally thereof.

The foregoing and other objects may be attained by means of the construction illustrated in the accompanying drawing, in which the figure is a perspective view of a necktie stretcher and supporter for the 35 larger end of a four-in-hand scarf or tie and made in accordance with this invention.

Referring to the drawing, *a* designates as an entirety the stretcher for the larger end of a scarf or tie, and is made from a single 40 piece of spring wire of the desired gage and resiliency, said stretcher comprising a straight member 1 bent at 2 and a slightly divergent member 3. The member 1 is bent at right angles to form a keeper arm 4, and 45 said arm is provided with a hook 5 bent to direct its ends toward the member 1, while a series of similar hooks 6 have their bills or ends directed in the opposite direction and formed on the terminal end of the arm 50 4. The divergent member 3 at its upper end is bent at right angles as at 7, and extends

to nearly a central point immediately above the hook 5, while said arm is bent upwardly as at 8 and provided with a suspending ring 9 at its end.

Four-in-hand scarfs and similar neckties are tubular in form and at the larger end of the tie, the point 2 of the stretcher is inserted, after the arm 3 has been swung over and engaged with the hook 5. After the 60 stretcher has been inserted, the member 3 is disengaged from the hook 5 and engaged with any one of the hooks 6 to hold the tie stretched laterally at its larger end.

From the foregoing it will be obvious that 65 a necktie stretcher made in accordance with this invention may be manufactured at low cost, is easy to insert in a tie for stretching the same, can be suspended upon a hook or nail, and is very efficient for its purpose.

Various changes may be made in the details of construction without departing from the spirit and scope of the invention as defined in the claim.

What is claimed is:—

A necktie stretcher comprising a straight member having its lower end bent rearwardly and diverging outwardly from said straight member forming an oppositely disposed member, said outwardly disposed member bent at right angles at the upper end thereof and terminating approximately at a point in vertical alinement with the lower end of said outwardly disposed member, and having a vertical handle formed 80 thereon, said straight member bent at right angles at the upper end thereof, forming a horizontally disposed keeper arm, a hook formed intermediate the ends of said horizontally disposed keeper arm and the end 85 bent downwardly therefrom adapted to receive the outwardly disposed member when in a contracted position, a plurality of hooks formed on said horizontally disposed keeper arm adjacent the outer end.

In testimony whereof I affix my signature in presence of two witnesses.

RALPH H. CHANDLER.
